CLAIM

The ornamental design for a full depth crate, as shown and described.

DESCRIPTION

FIG. 1 is a top plan view of a full depth crate showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a sectional elevational view taken along line 7—7 of FIG. 6;

FIG. 8 is a sectional elevational view taken along line 8—8 of FIG. 6;

FIG. 9 is a sectional plan view taken along line 9—9 of FIG. 3, the bottom support being eliminated for clarity of illustration;

FIG. 10 is a fragmentary enlarged scale sectional view taken along line 10—10 of FIG. 7;

FIG. 11 is a fragmentary enlarged scale sectional view taken along line 11—11 of FIG. 7;

FIG. 12 is a fragmentary enlarged scale sectional view taken along line 12—12 of FIG. 6;

FIG. 13 is a fragmentary enlarged scale sectional view taken along line 13—13 of FIG. 6;

FIG. 14 is a fragmentary enlarged scale sectional view taken along line 14—14 of FIG. 1; and,

FIG. 15 is a fragmentary enlarged scale sectional view taken along line 15—15 of FIG. 1.
